(57) **CLAIM**

The ornamental design for equipment for distribution or control of electric power, as shown and described.

DESCRIPTION

FIG. 1 illustrates a front perspective view of equipment for distribution or control of electric power.

FIG. 2 illustrates a front elevation view thereof;

FIG. 3 illustrates a right side view thereof;

FIG. 4 illustrates a left side view thereof;

FIG. 5 illustrates a rear elevation view thereof;

FIG. 6 illustrates a top plan view thereof; and,

FIG. 7 illustrates a bottom plan view thereof.

The broken lines in the drawings depict portions of the equipment for distribution or control of electrical power that form no part of the claimed design.

1 Claim, 7 Drawing Sheets(56)
